UNITED STATES PATENT OFFICE.

LIPA FEINGOLD AND DAVID FEINGOLD, OF BROOKLYN, NEW YORK.

DESIGN FOR A STICKPIN.

Application filed June 27, 1924. Serial No. 9,991. Term of patent 14 years.

To all whom it may concern:

Be it known that we, LIPA FEINGOLD and DAVID FEINGOLD, citizens of the United States, residing at Brooklyn, in the county of Kings and State of New York, have invented a new, original, and ornamental Design for a Stickpin, as shown in the accompanying drawing and described in the following specification.

The drawing shows a front view of stickpin, constituting our new design.

We claim:

The ornamental design for a stickpin as shown.

LIPA FEINGOLD.
DAVID FEINGOLD.
